DESIGN FOR A PORTABLE SUNDIAL

Louis Goodman, Los Angeles, Calif.

Application July 17, 1945, Serial No. 120,764

Term of patent 3½ years

(Cl. D42—8)

To all whom it may concern:

Be it known that I, Louis Goodman, a citizen of the United States, residing at Los Angeles, in the county of Los Angeles and State of California, have invented a new, original, and ornamental Design for a Portable Sundial, of which the following is a specification, reference being had to the accompanying drawing, forming a part thereof.

Figure 1 is a perspective view of a portable sundial showing my new design.

Fig. 2 is a plan view and Fig. 3 is a side elevation of the same.

I claim:

The ornamental design for a portable sundial, as shown.

LOUIS GOODMAN.
